(57) **CLAIM**

I claim the ornamental design for a suction head for a vacuum cleaner, as shown and described.

DESCRIPTION

FIG. 1 is a right side elevational view of a suction head for a vacuum cleaner showing my new design;

FIG. 2 is a left side elevational view of FIG. 1;

FIG. 3 is a front elevational view of FIG. 1;

FIG. 4 is a rear elevational view of FIG. 1;

FIG. 5 is a top plan view of FIG. 1;

FIG. 6 is a bottom plan view of FIG. 1;

FIG. 7 is a perspective view of FIG. 1;

FIG. 8 is a right side elevational view of a second embodiment thereof;

FIG. 9 is a left side elevational view of FIG. 8;

FIG. 10 is a front elevational view of FIG. 8;

FIG. 11 is a rear elevational view of FIG. 8;

FIG. 12 is a top plan view of FIG. 8;

FIG. 13 is a bottom plan view of FIG. 8;

FIG. 14 is a perspective view of FIG. 8;

FIG. 15 is right side elevational view of a third embodiment thereof;

FIG. 16 is a left side elevational view of FIG. 15;

FIG. 17 is a front elevational view of FIG. 15;

FIG. 18 is a rear elevational view of FIG. 15;

FIG. 19 is a top plan view of FIG. 15;

FIG. 20 is a bottom plan view of FIG. 15;

FIG. 21 is a perspective view of FIG. 15;

FIG. 22 is a right side elevational view of a fourth embodiment thereof;

FIG. 23 is a left side elevational view of FIG. 22;

FIG. 24 is a front elevational view of FIG. 22;

FIG. 25 is a rear elevational view of FIG. 22;

FIG. 26 is a top plan view of FIG. 22;

FIG. 27 is a bottom plan view of FIG. 22; and,

FIG. 28 is a perspective view of FIG. 22.
